UNITED STATES PATENT OFFICE.

BENJAMIN M. SMARR, OF DETROIT, MICHIGAN, ASSIGNOR TO GENERAL MOTORS CORPORATION, OF DETROIT, MICHIGAN, A CORPORATION OF DELAWARE.

TERMINAL CLIP FOR CABLE ENDS.

Application filed March 25, 1925. Serial No. 18,201.

This invention relates to improvements in terminal clips for cable ends.

It is an object of this invention to provide a clip for this purpose which, when once secured in assembled relation with the terminal, will firmly grip the latter and prevent accidental separation of these parts when, for example, it is desired to adjust the connections by a shifting of terminals.

10 It is a further object of this invention to modify a spade type of terminal so that while it may be initially inserted in place with the same facility as spade type terminals of usual construction, nevertheless when once assembled, will grip the cooperating terminal and prevent its accidental separation therefrom, an advantage heretofore confined to terminals of the closed end type. This object I have accomplished by the provision of bendable ears projected between the spaced arms of the terminal clip, these ears being straightened in the operation of assembly so as to grip the terminal and prevent separation of the parts. Preferably, this structure has been 25 combined with a terminal of the type having a portion of normal diameter adjacent the head and a portion of enlarged diameter remote from the head, whereby the terminal and terminal clip when assembled are held 30 not only against sidewise separation but also against endwise separation.

Referring now to the drawings:

Figure 1 is a plan view of the blank from which my terminal clip is formed;

35 Figure 2 is a plan view of the completely formed blank, the cooperating terminal being shown in section;

40 Figure 3 shows the terminal clip in assembled relation with the terminal prior to the forcing of the terminal into firm engagement with its support; while

Figure 4 shows the assembled terminal and clip after this operation has been performed.

45 Figure 5 is a section taken on line 5-5 of Figure 1 but on an enlarged scale. The bendable tongues are shown in dotted lines in the position they assume after deformation.

50 On the drawing, the reference character 2 indicates the blank from which the terminal clip is formed. This blank provides a cable gripping portion 4 comprising parts adapted to be firmly clamped around the cable end in the manner shown in Figure 2, and a terminal clip portion 6. The terminal clip portion 6 is roughly of the spade type for it comprises

spaced arms 8 and is adapted to be moved sidewise into straddling relation with the terminal, here indicated by the reference character 10. This terminal is here shown as a bolt provided with a screw head 11 although this construction of terminal is not essential to my invention.

Referring again to the terminal clip, it will be observed that the arms 8 are provided with inwardly directed elements or lugs 12, these lugs constituting the means for gripping the terminal hereinbefore referred to. In the completed clip shown in Figure 2 the lugs 12 extend downwardly at an angle to the plane of the clip in order to afford sufficient clearance to permit the passage of the shank 14 of the terminal 10 between them in assembling the connection. When thus assembled, as shown in Figure 3, the terminal 10 is forced firmly into engagement with support 16, with which it may or may not be in conducting relation. This operation results not only in firmly clamping the terminal clip between the terminal and the support but also effects the straightening of the lugs 12 so that they partially surround and grip the shank 14 of the terminal 10, as shown in Figure 4. The parts are thus securely held against accidental separation.

55 In order to further insure against separation of the terminal clip and terminal when once assembled, I have made use of a terminal having a portion 18 of normal diameter and a portion 20 of enlarged diameter, the latter portion being preferably provided by a rolled thread formed on the surface of the bolt. By this means the terminal clip and terminal are held against endwise as well as against sidewise separation when the terminal is disconnected from its support.

60 While I have shown and described one embodiment of my invention for purposes of illustration, I desire it to be understood that my invention is not limited to this specific form, but covers as well all modifications or adaptations coming within the scope of the following claims.

65 What I claim is:

1. The combination of a terminal having a portion of normal diameter and a portion of enlarged diameter, a clip comprising spaced arms adapted to straddle said terminal, means mounted on said terminal and cooperating with the terminal support for clamping the clip to the terminal, said clip be-

ing provided with a portion adapted to be permanently distorted by said clamping means to a position partially surrounding said portion of normal diameter, preventing its separation therefrom either laterally or axially.

2. In the combination as defined in claim

1, said distortable portion comprising inwardly extending tongues formed on the arms and normally spaced to clear the terminal.

In testimony whereof I affix my signature.

BENJAMIN M. SMARR.
